(57) **CLAIM**

The ornamental design for a protective cover for biosensor as shown and described.

DESCRIPTION

FIG. 1 is a perspective view of a first embodiment of a protective cover for biosensor showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 5; FIG. 11 is a perspective view of a second embodiment of the protective cover for biosensor; FIG. 12 is another perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; FIG. 19 is an enlarged view of portion 19 shown in FIG. 11; and, FIG. 20 is an enlarged view of portion 20 shown in FIG. 15. The dot-dash broken lines represent boundaries of the enlarged portions and form no part of the claimed design.

1 Claim, 20 Drawing Sheets
